UNITED STATES PATENT OFFICE.

EUGENE W. VOGEL, OF OAK PARK, ILLINOIS, ASSIGNOR TO CHICAGO RAILWAY SIGNAL AND SUPPLY COMPANY, OF CARPENTERSVILLE, ILLINOIS, A CORPORATION OF ILLINOIS.

ANNUNCIATOR.

1,337,299.

Specification of Letters Patent. Patented Apr. 20, 1920.

Application filed June 20, 1914. Serial No. 846,307.

To all whom it may concern:

Be it known that I, EUGENE W. VOGEL, a citizen of the United States, residing at Oak Park, in the county of Cook and State 5 of Illinois, have invented certain new and useful Improvements in Annunciators, of which the following is a specification.

My invention relates to an annunciator, and particularly to an annunciator suitable 10 for use in a switch tower, or like situation, to give notice by a visible and also an audible signal of the presence of a train upon a certain track.

The invention contemplates providing a 15 visible signaling mechanism capable of producing three signals, one to indicate a clear block, and the other two to indicate the presence of a train upon the block; and further, to provide an audible signaling mechanism, such as a bell or buzzer, which commences to operate when the train appears on 20 the block and is automatically silenced either when the train leaves the block, that is, when the visible signaling element dis- 25 plays the "clear" signal, or by the setting of the visible signaling mechanism from the position displaying the "train" signal into which it is automatically moved by the appearance of a train on the block, to the po- 30 sition displaying the other "train" signal, to which latter position the mechanism may be moved by the tower man through the agency either of an electrically operated mechanism controlled by a push button, or 35 the like, or by a pull rod or other suitable means.

In train annunciators of the type heretofore most commonly used, the visible signaling element or banner assumed only two 40 positions, one indicating a clear track and the other a train on the block. The banner automatically fell to the "train" position and the bell or buzzer started to ring when the train appeared on the block and the bell or buzzer continued ringing until the 45 train left the block, when it ceased automatically. The banner or visible signal was then reset by hand. As a result of the mode of operation the tower men very frequently 50 plugged the buzzer when a train stayed upon the block for any considerable length of time so as not to be annoyed by the con-

tinual ringing. When the train moved off the block it not infrequently happened, through carelessness, that the buzzer was 55 left plugged up and accidents resulted. To overcome this condition annunciators were devised in which the banner could be set back by hand to the "clear" position, and the buzzer thereby silenced. The disadvantage 60 of a device of this sort is that when the mechanism has been set back by the tower man to stop the bell, there is nothing to give indication that the train is still upon the block. If the train remains on the track 65 for any considerable time the tower man may forget that he has reset the annunciator and, relying on the indication of "clear" given by the banner, send another train in on the block to collide possibly with the 70 train already there.

My invention provides an annunciator in which the buzzer or other audible signaling device may be silenced in case the train remains for any considerable length of time 75 on the block by an operation which leaves a visible signal indicating that the track is not clear. Having reference to the particular embodiment of the invention hereinafter described provided with a chart or train 80 card divided to provide three signals, one "clear" and the other two "train," the banner may be moved by the tower man from one "train" position to the other and the buzzer thereby silenced. When the train 85 moves off the block the banner is automatically returned to the "clear" position from this second or manually set "train" position.

The invention consists in the novel arrangements, constructions and devices to be 90 hereinafter described and claimed for carrying out the above stated object, and such other objects as will appear from the following description.

The invention is illustrated, in a pre- 95 ferred embodiment, in the accompanying drawings wherein—

Figure 1 is a front elevation with the electric circuits and certain devices shown diagrammatically;

Fig. 2, a longitudinal sectional view of the annunciator showing the banner in the "clear" position;

Fig. 3, a longitudinal sectional view of

the lower part of the mechanism showing the banner in the first or automatically set "train" position;

Fig. 4, a sectional plan taken on line 4—4 of Fig. 3;

Fig. 5, a view, similar to Fig. 3, showing the banner in the second or manually set "train" position;

Fig. 6, a view, in perspective, of a portion 10 of the lever supporting the banner, showing particularly the dog employed for holding the banner in its two upper positions, and

Fig. 7, a view, in perspective, of the bracket 15 in which the banner supporting lever is pivoted.

Like characters of reference designate like parts in the several figures of the drawings.

Referring to the drawings, 10 designates a frame to which is secured an insulating block 11 on which the operative parts of the annunciator are mounted, and 12 a housing inclosing said mechanisms and formed with an aperture 13 closed by a piece of glass 14, held in place by clips 15. The banner 16, 20 carried on a lever 17 pivoted to a clevis 18 of a bracket 19, carries a chart divided into three sections 20, 21 and 22, one above the other. The display of the middle section indicates a clear track. The upper and 25 lower sections are displayed to give indication of a train on the block. The banner is automatically moved to display the upper section 20 when a train moves upon the block. It may be set by the tower man to 30 a position to display the section 22 to silence the buzzer designated 23. When the train moves off the block the banner is returned to the "clear" position from whichever "train" 35 position it may be occupying. The upper or automatically set signal 20 may, if desired, 40 be given a legend, coloring or other device which will distinguish it from the lower train signal 22. The block or section of track in connection with which the annunciator is used is designated 24. 45 25 designates the track battery, and 26 the track relay which drops its armature 27 when the train moves upon the block, closing a circuit at 28 which causes the banner to move 50 from the "clear" position to the position displaying the upper "train" signal 20, as will be hereinafter described.

The banner lever 17 is held in its intermediate position, to display the "clear" signal, 55 by the following devices: The lever 17 is formed with an arm 29 to which is pivoted a dog 30 against opposite sides of which bear two leaf springs 31, 32 which yieldably maintain the dog in position to 60 engage other parts to be described. The dog is engaged by a shoulder 33 of a tripping arm 34 which constitutes the armature of an electromagnet 35. The magnet is supported on a shelf 36 secured to the insulating block 11, the shelf being formed with

a depending bracket 37 in which the armature or tripping arm 34 is pivoted on a pin 38.

When a train moves on the block 24, causing the relay 26 to drop its armature 27, the 70 magnet 34 is energized by a battery 38', the circuit of which is designated 39 (Fig. 1). The armature for tripping arm 34 is drawn up to the magnet and this releases the dog 30 so that the arm 17 falls carrying the banner to the position shown in Fig. 3 in which the upper "train" signal 20 is displayed. 75

The buzzer 23 is set in operation when signal 20 is displayed by operation of the following devices: The buzzer is arranged 80 on a circuit 40 in which is a battery 41, a pair of spring contacts 45, 46 which are secured to the insulating block 11 and normally stand apart. The wire 40 is connected to a binding post 47 electrically connected with the contact 45 and to a binding post 48 electrically connected with the contact 46. The arm 29 of the banner lever 17 is provided with a button 49 of insulating material which comes against the contact 90 spring 45 when the banner drops to the position shown in Fig. 3, forcing it against the contact spring 46.

A pull rod 50 is attached to the inner end of the lever 17 for raising the same to display the "train" signal 22. By doing this the buzzer circuit is broken between the contacts 45, 46, which separate as soon as the button rides away from contact 45, so that the buzzer is silenced. When the banner is 100 raised to this position (Fig. 5) the dog 30 engages a tooth 51 on a depending portion 52 of the armature 33 so that the banner is held in this position as long as the magnet 34 remains energized. 105

The same movement of the lever 17 may be effected by means of a resetting magnet 53, and the circuit 54, a shunt from circuit 40, which is closed by a push button 57 located at any convenient point in the tower 110 house. The armature 58 of the magnet 53 moves in guides 59 on the magnet and is provided with a pair of uprights 60 connected by a cotter pin 61 which extends through a slot 62 formed in the lever 17 on the other side of the pivot pin 63 from the banner. The movement of the lever 17 in the direction to display the signal 20 is limited by a cross piece 64 forming part of the bracket 19. 115

The housing 12 is held in position by a screw 65 which enters a lug 66 formed on the shelf 35.

The operation of the apparatus above described may be summarized as follows: 125 When the block 24 is clear the circuit of the magnet 35 is open at 27, 28. The armature 34 of the magnet is down and its shoulder 33 engages the dog 30 holding the lever 17 in its intermediate position so that the 130

"clear" signal is displayed at the window opening 18. The mechanism is shown in this position in Figs. 1 and 2. When a train moves on the block battery 25 is cut out, 5 relay 26 drops its armature 27 closing the circuit of magnet 35 and the magnet attracts its armature 34, releasing the dog 30 which allows the banner to drop to its lower position displaying the train signal 20. The 10 button 49 bears against the contact spring 45 pressing it against the contact spring 46 which completes the circuit through buzzer 23. The mechanism is shown in this position in Figs. 3 and 4. To silence the buzzer the 15 tower man pulls down the rod 50 or presses the push button 57 so as to raise the banner lever 17. If the train by this time has moved off the block, causing magnet 35 to drop its armature, the dog 30 will engage with 20 the shoulder 33 so as to hold the banner in the "clear" position. With the train still on the block, the armature 34 is in its upper position against magnet 35 so that in order to hold the banner up the lever 17 must be 25 rocked until the dog 30 engages the catch 51 on the armature. In this position, which is the position shown in Fig. 5, the lower train signal 22 is displayed and the mechanism is set so that when the train moves 30 off the block, the banner is automatically returned to "clear." That is, assuming that the parts are in the position shown in Fig. 5 and the armature 34 is dropped by the energization of magnet 35 which takes place 35 when the train moves off the block, the dog 30 disengaged from the catch 51 will be intercepted and held by the shoulder 33. Should the banner not be manually operated to open the circuit controlling the audible 40 signal until after the train has cleared the track, the dog 30 will not engage the catch 51 but will engage the shoulder 33 to hold the banner in the "clear" position. It will be released from this position—the "clear" 45 position of Fig. 2—allowing the banner to fall to the lowermost position, that of Fig. 3, when another train makes its appearance on the block in the manner above described.

While the invention is shown and described in a preferred embodiment, modifications might be devised without departure from the principles of the invention. Therefore I do not wish to be understood as limiting the invention to the particular constructions, arrangements and devices specified except so far as said constructions, arrangements and devices are specifically made limitations in certain of the claims herein.

I claim:

1. In a train annunciator, the combination 60 with a visual signaling element adapted to assume an upper, a lower and an intermediate position; of an audible signaling mechanism, actuating devices therefor operable only when said visible element is in the 65 lower position; means for raising said element from the lower to either of the other positions; a spring pressed pivoted dog on said visual signaling element; a tripping arm formed with catches adapted to be engaged by said dog, one of them to hold said element in the upper position and the other to hold the same in the intermediate position; and mechanism for controlling the movements of said tripping arm so as to 70 effect one or the other of said engagements. 75

2. In a train annunciator, the combination with a visual signaling element adapted to assume an upper, a lower and an intermediate position; of an audible signaling mechanism, actuating devices therefor operable only when said visual element is in the lower position; means for raising said element from the lower to either of the other positions; a spring pressed pivoted dog on said 80 visible element, a tripping arm formed with catches adapted to be engaged by said dog, one of them to hold said element in the upper position and the other to hold the same in the intermediate position, and mechanism 85 for controlling the movements of said tripping arm so as to effect one or the other of said engagements, said dog, when released from the engagement holding the element in the upper position, being adapted to come 90 into engagement with the catch on said tripping arm which holds said element in the intermediate position. 95

3. In a train annunciator, the combination with a signaling element adapted to assume 100 an upper, a lower and an intermediate position; of means for raising said element from its lower to either of its other positions; a spring pressed pivoted dog on said element; a tripping arm formed with catches adapted 105 to be engaged by said dog, one of them to hold said element in the upper position and the other to hold the same in the intermediate position, and mechanism for controlling the movements of said tripping arm 110 so as to effect one or other of said engagements.

EUGENE W. VOGEL.
